UNITED STATES PATENT OFFICE.

ARNOLD V. BROWN, OF WORCESTER, MASSACHUSETTS, ASSIGNOR TO AMERICAN NARROW FABRIC COMPANY, A CORPORATION OF MASSACHUSETTS.

DETACHABLE CONNECTING DEVICE FOR HOSE SUPPORTERS.

Application filed November 22, 1922. Serial No. 602,639.

To all whom it may concern:

Be it known that I, ARNOLD V. BROWN, a citizen of the United States, residing at Worcester, in the county of Worcester and State of Massachusetts, have invented a new and useful Detachable Connecting Device for Hose Supporters, of which the following is a specification.

This is in part a continuation of my application Serial No. 576,782, filed July 22, 1922, but contains an improvement thereon.

This invention relates to a device for connecting two pieces of fabric, as for example tape or elastic, in such a way that they can be detached from each other readily but will not become disconnected accidentally.

The principal object of the invention is to provide a device for this purpose which will be simple and convenient and certain in its action and will be very inexpensive to make in large quantities.

Reference is to be had to the accompanying drawings, in which—

Fig. 1 is a front view of a hose supporter of the ordinary type having its two parts connected by a device constructed in accordance with this invention;

Fig. 2 is a similar view of the connector removed from the supporter;

Fig. 3 is a similar view of a modification; and

Figs. 4 and 5 are like views of other modifications.

In the form shown in Figs. 1 and 2, the device is made of a stamping of sheet metal and comprises a lower bar 10, a middle bar 11 and a top bar 12, all practically parallel. The lower bars 10 and 11 are spaced materially apart and integrally connected at both ends so as to provide an enclosed rectangle formed of the stamped metal with its corners and ends all rigid. One of these ends, as 13, is extended beyond the middle bar 11 and has at its end the top bar 12 projecting from it parallel with the other two bars 10 and 11. This top bar 12 is provided at its opposite free end with a hook 14 and is not connected with the body of the device at that end. This hook involves a short end substantially parallel with the top bar 12 and spaced only slightly from it to just permit the edge of the tape to lie in the space. It also furnishes a means by which this bar 12 can be inserted through a sewed loop in the bottom of the fabric and the hook 14

extended under it, as shown in Fig. 1, so as to detachably hold the loop and yet prevent any accidental detachment. This furnishes a simple and convenient way of connecting this metallic connector detachably to the bottom of a garment, tape or elastic. As it would be difficult to form a hook with such a narrow space I provide an open circular notch 17 at the end of the space. This permits of the insertion of the necessary tool in the process of manufacture.

The rectangle formed by the ends and the two bars 10 and 11 can be used for connection of a piece of tape or elastic below, without any additional features and that is the way the device is constructed and used, as shown in Fig. 3. In the form shown in Figs. 1 and 2, however, a slide 15 is mounted on the two ends of the lower rectangle capable of sliding up and down in the space between the two bars 10 and 11. This slide is slit longitudinally at 19 for the reception of the lower tape or elastic which can be secured to it in any of the ordinary ways to avoid providing a sewed loop. This also provides a means of adjusting the webbing by passing the webbing over, around and back under the slide 15. By this procedure the webbing is securely locked which thereby provides a means of adjustment of the fabric, a very desirable thing. There is no necessity of sewing the webbing also. In view of the above, no further description of Fig. 3 is necessary.

In the form shown in Fig. 4, the upper bar 12 and hook 14 are used as in the other cases, but in place of the lower parts is a similar bar 20 and hook 21 integrally connected with the upper bar. These parts can be made of sheet metal stamping, if desired, as shown in Fig. 5, but can be made of a piece of wire as in Fig. 4. If that is done, the connection between the two bars 12 and 20 is strengthened by using a sheet metal clip 22 bent around and surrounding the two corners and stiffening the connection of the two bars 12 and 20 with a connecting piece between them. In the stamping shown in Fig. 5 the bars 12 and 20 are made tapering from end to end, being widest at the ends bearing the hook. This tapering is slight but sufficient to compensate for the slight spring of the bars under strain and inner face parallel when in use. The same construction is used in Figs. 1, 2 and 3. If

this were not done any strain heavy enough might spring the ends apart a little and leave the bars in a diverging position. Then the strain would tend to pull the tape off the 5 bars.

In all the forms the circular notches 17 are used. In each case the external end of the hook is substantially parallel with the bars to prevent accidental detachment from 10 the tape.

This invention provides a very inexpensive form of device for the purpose intended and insures the ready detachment of the depending tape or elastic without bending the 15 metal parts of the connecting piece or distorting them in any way. The edges can be finished up so as not to injure the fabrics when the device is used. It is also all located in a plane so it can be formed of a metal 20 stamping of the simplest character or of wire.

Although I have illustrated and described only three forms of the invention, I am aware of the fact that other modifications can be 25 made therein by any person skilled in the art without departing from the scope of the invention as expressed in the claims. Therefore, I do not wish to be limited to all the details of construction herein shown and 30 described, but what I do claim is:—

1. As an article of manufacture, a connector for the purpose described comprising a piece of sheet metal provided with three parallel bars spaced apart, two of said bars 35 being integrally connected with each other at both ends and with the third one at one

end, the third bar having a hook thereon, the connection between the first two bars at each end consisting of an end member, the two end members being parallel with each 40 other, and a slide for connection with the fabric or tape mounted on said two end members.

2. As an article of manufacture, a connecting device for a hose supporter or the 45 like comprising a pair of bars located practically parallel with each other and spaced apart, one of said bars having a free end provided with a reverse hook for placement behind a piece of fabric mounted thereon 50 and having an open sided enlarged circular notch at the point at which the hook is connected with the bar.

3. As an article of manufacture, a connecting device for a hose supporter comprising 55 a pair of bars in substantially parallel position but tapering in width from end to end and connected together at their narrower ends so as to be spaced apart, and provided with reverse hooks at their free 60 end each having a circular notch forming the inner boundary of the hook.

4. As an article of manufacture, a connecting device for a hose supporter comprising 65 a pair of bars in substantially parallel position but tapering in width from end to end and connected together at their narrower ends so as to be spaced apart farther at their connected ends than at their free ends.

In testimony whereof I have hereunto 70 affixed my signature.

ARNOLD V. BROWN.
